[57] CLAIM

The ornamental design for a carpet designer's iron, as shown and described.

DESCRIPTION

FIG. 1 is a right side elevational view of a carpet designer's iron showing my new design, the left side being a mirror image;

FIG. 2 is a top plan view thereof;

FIG. 3 is a bottom plan view thereof;

FIG. 4 is a rear elevational view thereof; and

FIG. 5 is a front elevational view thereof.

The conventional electrical cord has been shown fragmentarily in FIGS. 1-4 for ease of illustration.

FIG. 2FIG. 4FIG. 1FIG. 5FIG. 3
